UNITED STATES PATENT OFFICE.

GOTTLOB HONOLD, OF STUTTGART, GERMANY, ASSIGNOR TO THE FIRM OF ROBERT BOSCH, OF STUTTGART, GERMANY.

ELECTRICAL REGULATING DEVICE.

1,221,327.

Specification of Letters Patent.

Patented Apr. 3, 1917.

Application filed November 13, 1913. Serial No. 800,765.

To all whom it may concern:

Be it known that I, GOTTLÖB HONOLD, engineer, a subject of the German Emperor, residing at Stuttgart 4-8 Militärstrasse, 5 Germany, have invented certain new and useful Improvements in Electrical Regulating Devices, and do hereby declare the following to be a full, clear, and exact description of the invention, such as will enable 10 others skilled in the art to which it appertains to make and use the same.

This invention relates to electric circuit regulators of the type comprising a container holding a mass of finely divided resistance material, such as carbon, which is subjected to the variable pressure of a pressure member responsive to the magnetism of an electromagnet.

In regulators of this character adapted for 20 electric circuits carrying considerable currents, the cross sectional area of the mass of finely divided material must be comparatively large to avoid overheating the mass. When the area of the mass is large, the particles forming the exposed surface layer are 25 apt to become deranged, by being heaped up at one or more places and forming depressions at other places, thereby forming an irregular surface. As a result the pressure 30 of the pressure member will not be uniform throughout the mass, and, of course, the resistance offered by the mass to the passage of the current will not be uniform, whereby the effectiveness of the regulator will be lessened.

The object of this invention is to provide a 35 regulator of this type in which the formation of an irregular surface of the mass of finely divided material is prevented. This 40 object may be accomplished in several ways in accordance with my invention, as by so constructing the device that the surface layer of the mass is exposed to the atmosphere, thereby preventing shifting of the material 45 due to suction caused by the upward movement of the pressure member; or by dividing the mass into a plurality of columns of such small cross section that there can be no material irregularity of the surface of the mass; 50 or by so guiding the pressure member during movement that its contacting surface will at all times be maintained parallel with the surface layer of the mass; or by combining these separate means.

In the accompanying drawings, in which 55 are shown several embodiments of the invention, and in which the same reference character refers to a similar part throughout the several figures,

Figure 1 is a sectional view of one form of 60 my regulator;

Fig. 2 is a view similar to Fig. 1 showing another form thereof;

Fig. 3 is a view partly in plan and partly 65 in section of the regulator shown in Fig. 1;

Fig. 4 is a view similar to Figs. 3 and 4 showing another form of regulator;

Fig. 5 is a similar view of still another 45 form;

Figs. 6 and 7 are detail plan views of parts 70 of the regulator shown in Fig. 5;

Fig. 8 is a sectional view of a modified form of pressure member;

Fig. 9 is a plan view thereof;

Fig. 10 is a sectional view of another form 75 of regulator in which the mass of finely divided resistance material is divided into a plurality of columns by partitions within the container;

Figs. 11, 12 and 13 illustrate various ways 80 in which the partitions may be formed;

Fig. 14 is a sectional view of a regulator 85 in which the pressure member is maintained parallel with the surface layer of the resistance mass; and

Fig. 15 is a similar view showing another 85 form thereof.

The suction caused in prior types of regulators of this kind by the movement of the pressure member away from the exposed surface of the resistance mass, and the currents of air produced thereby, may be eliminated by exposing the surface layer of the mass *h* to the atmosphere throughout its extent, and in Fig. 1 there is shown a form of 90 construction for accomplishing this result. The pressure member *a* of that figure is provided with a plurality of perforations or 95 passageways extending therethrough and also with longitudinal passageways open to the atmosphere and communicating with the surface layer by a plurality of perforations. These passageways permit the atmospheric air to have access to the surface layer of the mass *h* at a plurality of points over the area covered 100 by the pressure member *a* and, consequently, when the pressure member is raised, 105 no suction is produced and, therefore, there

is no air current tending to shift the material to produce an uneven surface.

- Referring to Fig. 2, a similar result is produced by providing the container with a plurality of insulating tubes open at their lower ends to the atmosphere and with their upper ends substantially flush with the exposed surface of the mass *h*. In this form of regulator, the pressure member *a* need not be perforated as suction is prevented by air flowing into the container through the tubes when the pressure member is raised, but recesses are provided in the underside of the pressure member as shown, to accommodate the tubes.
- Referring to Fig. 4, the surface of the mass *h* is exposed to the atmosphere by placing between that surface and the pressure member, one or more layers *l* of a conducting material, such as carbon, the grains of which are coarser than the grains forming the rest of the mass *h*. The grains forming the layer or layers *l*, are preferably of spherical form and permit the air to pass between them, thus preventing suction when the pressure member rises. In this construction, it is unnecessary to provide the pressure member with perforations or recesses, and a plate *k* preferably of carbon may, if desired, be fastened to the pressure member *a* to make better contact with the resistance material.

Referring to Figs. 5, 6 and 7, the pressure member comprises a perforated plate *e* secured to and spaced from the under surface of the body portion *a* by bolts *d*, the plate being preferably of metal. The lower surface of the plate *e* is covered by wire gauze *f*, of small mesh, which is secured to the plate in any suitable manner as by means of a ring *g* soldered at its edge to the plate *e*. This plate is preferably in the form of a wheel, as shown in Fig. 8, and to prevent the gauze *f* from being bent, it may be soldered to the spokes. In order to guide the pressure member during its movements, the body portion *a* may have secured thereto an annular strip *b* of pliable fabric clamped around its periphery between the insulating rings *i* which form a lining for the container *c*.

In the modification of the pressure member shown in Figs. 8 and 9, the gauze *f* is secured directly to the under surface of the body portion *a* and prevents the carbon grains from passing through the perforations extending through the body portion *a*.

In each of the modifications of the regulator thus far described, it will be seen that substantially the entire upper surface of the mass of finely divided material is exposed to the atmosphere. Therefore, the movement of the pressure member away from the mass does not produce suction, and, consequently, there is no tendency for the mate-

rial forming the surface layer to become deranged.

Referring to Fig. 10, the container *c* is provided with partitions *p* of insulating material which divide the mass of resistance material into a plurality of columns *q* of small cross section. The cross sectional area of these columns is so small that, when the pressure member *a* rises the surface of the mass will be disturbed but slightly, if at all, thereby preventing any objectionable shifting of the material.

The partitions *p* may be arranged in various ways, as shown, for example, in Figs. 11, 12 and 13.

Fig. 14 shows an electromagnet *m* having the form of a pot magnet and having a shaft *o* carrying a pressure member *a*. The upper end of the shaft is secured to a steel membrane *s* which is clamped at its periphery by the cover *t* and the pressure member *a* has secured thereto an annular strip *b* of pliable fabric clamped at its periphery between the insulating ring *i* and a shoulder on the container *c*. The strip *b* and the membrane *s* form guiding means for insuring that the pressure member during its movements will be maintained parallel with the surface layer of the mass.

Fig. 15 shows a pressure member made up of the perforated body portion *a* and the gauze *f* and the spring system *u*, *u'* and *v*. The electromagnet *m*, shown as a pot magnet, has a shaft *o* which carries the pressure member and which passes through a central bore of larger diameter in the magnet. The spring *u*, which is clamped at its periphery by the cover *t*, is provided with a tongue *u'* secured at its inner end to a ring *w* mounted with slight play upon a pin *x* on the upper end of the shaft *o*. A closed yoke spring *v* is also secured to the ring *w* and is provided with an adjustable tensioning device as shown. The tongue *u'* is tensioned on one side and is of such length that the tilting action resulting from the circular movement of its free end practically disappears, as a result of the slight movement of the pressure member. The strip *b* is sufficiently loose to permit the small up and down movements of the pressure member, and any tendency of the pressure member to assume an inclined position is prevented by the springs *u* and *v*, which, however, do not prevent the substantially frictionless movement of the pressure member. The strip *b* and the tongue *u'* form guiding means producing movements of the pressure member of substantial parallel translation. By providing communication between the atmosphere and the exposed surface of the resistance mass *h*, and also providing such guiding means for the pressure member, there is produced an effective regulating device for electric circuits carrying considerable currents.

Reference is made to my copending application, Serial No. 807,877, filed December 20, 1913, which is directed among other things to parallel guiding means for the pressure member.

Having thus described my invention, what I claim is:

1. In a regulator for electric circuits, a container, a mass of finely divided resistance material therein, and a magnetically-responsive pressure member effective on the mass to vary the resistance thereof, said regulator being provided with ventilating means communicating with the resistance material for maintaining a uniform surface distribution of the resistance material during the movement of said pressure member.
2. In a regulator for electric circuits, a container, a mass of finely divided resistance material therein, and a magnetically-responsive pressure member effective on the mass to vary the resistance thereof and being provided with ventilating means preventing suction on the exposed surface of the resistance mass upon movement of said pressure member away therefrom.
3. In a regulator for electric circuits, a mass of finely divided resistance material, a container therefor, and a magnetically-responsive pressure member effective on the mass to vary the resistance thereof, the surface of said mass which lies beneath said pressure member being exposed to the atmosphere.
4. In a regulator for electric circuits, a mass of finely divided resistance material, a container therefor, and a magnetically-responsive pressure member effective on the mass to vary the resistance thereof, the surface of said mass which lies beneath said pressure member being exposed to the atmosphere at a plurality of points.
5. In a regulator for electric circuits, a mass of finely divided resistance material, a container therefor, and a magnetically-responsive pressure member effective on the mass to vary the resistance thereof, said pressure member providing communication be-

tween the surface of said mass and the atmosphere.

6. In a regulator for electric circuits, a mass of finely divided resistance material, a container therefor, and a magnetically-responsive pressure member effective on the mass to vary the resistance thereof, said pressure member being provided with a plurality of perforations to expose the surface of said mass to the atmosphere at a plurality of points.

7. In a regulator for electric circuits, a mass of finely divided resistance material, a container therefor, and a magnetically-responsive pressure member effective on the mass to vary the resistance thereof, said pressure member providing communication between the surface of said mass and the atmosphere, and gauze on the contacting surface of the pressure member.

8. In a regulator for electric circuits, a container, a mass of finely divided resistance material therein, a magnetically-responsive pressure member effective on the mass to vary the resistance thereof, ventilating means for maintaining a uniform surface distribution of the resistance material during movement of said pressure member, and guiding means producing movements of the pressure member of substantial parallel translation.

9. In a regulator for electric circuits, a container, a mass of finely divided resistance material therein, a magnetically-responsive pressure member effective on the mass to vary the resistance thereof and being provided with ventilating means preventing suction on the exposed surface of the resistance mass upon movement of said pressure member away therefrom, and guiding means producing movements of the pressure member of substantial parallel translation.

In testimony whereof I have affixed my signature, in presence of two witnesses.

GOTTLÖB HONOLD.
